UNITED STATES PATENT OFFICE.

ADOLPH M. SCHICK, OF WHEELING, WEST VIRGINIA.

MECHANICAL DISPLAY APPARATUS.

Application filed December 15, 1926. Serial No. 155,071.

This invention relates broadly to advertising and display apparatus, and it has for its primary object to provide a novel mechanical structure embodying rotary members which are adapted for carrying a plurality of inscriptions or legends and which are periodically rotated for successively presenting such inscriptions to view.

A further object is to provide a mechanism of the character mentioned which is adapted for use in the show windows of shops, stores and the like, or which may be carried upon the rear ends of road vehicles, as trolley cars and automobiles, and which, in the former case, may be actuated by a magnet coil, intermittently energized, and which, in the latter case, may be actuated from time to time by an inertia controlled weight.

A still further object is to provide, in association with a device of the character referred to, a figure or figures simulating animate objects which are in like manner actuated to make certain movements in simulation of actual movements of such objects, thereby to attract the attention of observers.

With these and other objects in view, the invention resides in the features of construction, arrangement of parts and combinations of elements, which will hereinafter be fully described, reference being had to the accompanying drawings, in which—

Figure 1 is a front elevation of the invention having associated therewith electrical means whereby it may be actuated intermittently, a portion of the front wall of the casing being broken away;

Figure 2 is a section on line 2—2, Fig. 1;
Figure 3 is an upper end view of the same;
Figure 4 is an enlarged detail view of the 10 ratchet and pawl mechanism;

Figure 5 is an enlarged end elevation of one of the rotary inscription carriers, showing the letter-carrying members or blocks mounted thereon;

Figure 6 is an enlarged detail section showing a means of connecting the actuating means to the movable member, or arm, of the figures shown in Fig. 1;

Figure 7 is a view similar to Fig. 1, showing an inertia controlled weight arranged to actuate the inscription carriers;

Figure 8 is a section on line 8—8, Fig. 7; and

Figures 9 and 10 are enlarged views in 55 end and front elevation, respectively, of a removable letter carrying member.

Referring to said drawings, 1 designates a casing, herein shown as rectangular in front and end elevation. Journaled within said casing, as upon rigidly carried vertical supports 2, are the opposite ends of a plurality of horizontally disposed inscription carriers 3, hereinafter termed rollers, each of which is made polygonal in end elevation, providing a plurality of longitudinally extending flat faces, each designed to carry thereon an inscription or legend which is readable through a window slot 4 provided in the front wall 1^a of said casing. While such inscriptions may be applied directly to said roller faces, it is preferred that the same be formed by successions of interchangeable letter bearing blocks 5, which are suitably mounted on the faces of the rollers. As herein shown for illustrative purposes, each 75 block 5 carries on the rear face thereof a horizontally disposed dove-tail tongue 5^a adapted to be inserted lengthwise and to be slidable to position in a longitudinal channel 6 of like form provided therefor in each 80 of said roller faces.

Suitable gearing is provided whereby rotary motion imparted to one of the rollers 3 is communicated to the remaining rollers, thus providing for simultaneous movement 85 of said rollers. As herein illustrated, motion imparted directly to the middle of the three rollers shown is communicated to the upper roller through intermeshing gears 7 and 8 respectively carried thereby, and in 90 like manner the gear meshes with a gear 9 carried by the lower roller for effecting drying of the latter.

The directly driven roller carries upon an end thereof a ratchet wheel 10 provided with a number of teeth 10^a corresponding to the number of inscription faces borne by the rollers; and engaged with said ratchet is a pawl 11 carried by an end of an angular lever 12 which is pivotally mounted intermediate its ends in an appropriate position, as upon the bracket 13 carried by the adjacent end wall of the casing 1. A weight 14 borne by the opposite end of said lever normally occupies a pendent position, holding the lever in substantially vertical position, as shown in Figs. 1, 2, 7 and 8, being maintained in said position by the force of gravity, thus normally maintaining the ratchet 10 and the roller stationary. However, when the weighted lower end of the lever is swung back to, or toward, the posi-

tion shown in broken lines in Fig. 8, or when the casing 1 is rocked back, as shown in broken lines in Fig. 2, the pawl 11 is carried forward to the extent that the ratchet is thereby rotated throughout the fraction of a revolution required to present in register with a window opening or slot 4 of the casing the next successive face of the ratchet carrying roller.

10 While any other appropriate type of actuating mechanism may be employed, as when the apparatus is employed in show windows, I have shown in Figs. 1 and 2, actuating means comprising an electromagnet 15 of bar form or of a type which is designed to be energized intermittently, as through a time controlled switch (not shown) and which is adapted, when energized, to act upon a metal block 17 for rocking the casing 1 rearward upon a hinge-like support 16, as shown in broken lines in Fig. 2. When the casing is so rocked, the weighted arm gravitates to the extent that advance rotation of the ratchet is actuated, as hereinbefore explained. When the magnet 15 is again deenergized, the casing returns by gravity to its normal upright position and the pawl 11 is retracted to the point where it engages the next succeeding tooth of the ratchet.

15 The casing 1 may be rigidly mounted upon the rear end of an automobile or other vehicle, in which case the weight 14 swings forward toward the rear wall of the casing by reason of its own inertia upon a more or or less sudden retardation of the velocity of the vehicle, as when the brakes are applied. Such movement of the weight from its normal position, shown in full lines in Fig. 8, substantially to the position shown in broken lines in said figure, causes the pawl 11 to advance the ratchet 10 to rotate for presenting to the window slots of the casing the next succeeding inscription-bearing faces of the rollers 3.

As shown in Figs. 1, 2 and 3, one or more figures or images of animate objects, as the figures 18 may be superposed on the casing 1 at or adjacent to the rear wall of the latter, each having a pivotally mounted part or member, as an arm 19, which is adapted to be moved from time to time for attracting attention thereto. The mechanism herein shown for illustrative purposes, whereby

55 said arms are actuated comprises a short lever arm 20 fixed on each arm 19 and connected by a vertically disposed rod 21 to an end of a lever 22 which is pivoted intermediate its ends upon a bracket 23 fixed on said rear wall of the casing. The opposite end of said lever 22 is connected by a pivoted link 25 to the pawl-carrying lever 12 hereinbefore referred to, being directed through a slot 24 provided in said casing wall. When the casing rocks back to the broken line position shown in Fig. 2, the weighted lever 12 acts through the intermediate connections described to swing the arms 19 in a more or less life-like manner to elevated positions.

60 What is claimed is—

1. In a display mechanism, a pivoted casing, rollers journaled within said casing, each roller having a plurality of inscription-bearing faces adapted to be successively exposed through the front of said casing, a ratchet carried by one of said rollers, a member pivoted upon a fixed part of the casing, a pawl carried by said member for operatively engaging said ratchet, a weight normally maintaining said member in a predetermined position relative to the casing, and electrical means whereby said casing may be rocked on its pivotal mounting relative to said weight for imparting rotary movement to said one roller, and gearing between said one roller and the other rollers whereby rotation of the former is simultaneously communicated to the latter.

75 2. In a display apparatus for vehicles, the combination with a casing having journaled rotative devices provided with inscription-bearing faces adapted to be successively displayed, and means for intermittently advancing said devices, said means including a pivoted member normally held by gravity in a predetermined position relative to said casing and shiftable from said position by reason of its own inertia upon retardation of the velocity of the casing-carrying vehicle, of means for attracting attention to said devices, said means comprising a pivoted figure located exterior to the casing, and link and lever mechanism intermediate said gravity controlled member and said pivoted figure whereby movement of the former imparts to the latter animated movements.

80 3. In testimony whereof, I affix my signature.

ADOLPH M. SCHICK.
